UNITED STATES PATENT OFFICE

2,420,500

ROTARY CULTIVATOR

John V. Schug, Paragould, Ark.

Application December 23, 1943, Serial No. 515,410

2 Claims. (Cl. 97—40)

1

The present invention appertains to new and useful improvements in cultivators of the rotary type.

An important object of the invention is to provide a cultivator having rotary cultivator units operating both transversely and longitudinally of the rows being cultivated.

Another important object of the invention is to provide a rotary type cultivator which employs rotary elements which dig at the roots of the growths to be eliminated, to the end that many types of weed growths will be permanently destroyed.

Still another important object of the invention is to provide a cultivator having both longitudinal and transverse cultivating elements and wherein drive means is employed for positively driving these elements in a sure acting and substantially foolproof manner.

Other objects and advantages of the invention will become apparent to the reader of the following description.

In the drawings—

Figure 1 represents a side elevational view of the cultivator.

Figure 2 is a top plan view.

Figure 3 is an enlarged sectional view taken substantially on the line 3—3 of Figure 1.

Figure 4 is a fragmentary sectional view showing one of the blocker type cultivator units.

Figure 5 is a fragmentary sectional view showing a modification of the blocker type unit disclosed in Figure 4.

Figure 6 is a side elevational view of another form of cultivator wheel.

Figure 7 is a fragmentary detailed sectional view of the gear box.

Referring to the drawings wherein like numerals designate like parts, it can be seen that numeral 5 denotes a rectangular-shaped frame having side members *a*, *a* and end members *b*, *b*. Situated under the frame 5 is a frame 6 which has side members *c*, *c* and end members *d*. A cross member 7 bridges the side members *c*, *c*. Link members 8 support the forward end of the frame 6, while the rear end of the frame is pivotally connected as at 9 to the lower end of a lever 10, which has a detent 11 engageable with a quadrant gear 12. Obviously, by actuating the lever 10 and setting the detent at the desired position on the gear 12, the elevation of the frame 6 can be adjusted.

A shaft 13 is disposed through suitable bearings 14 on the frame 5 and the shaft 13 is equipped with wheels 15 suitably secured thereto.

2

A shaft 19 which is journaled through the side members of the frame 6 carries cultivator units 20, preferably four in number as shown in Figure 2.

5 The shaft 19 extends through a gear box and has beveled gears 22 thereon and within the box meshing with a bevel gear 23 carried by a counter-shaft 24. This counter-shaft 24 extends longitudinally of the frame 6 and at its forward 10 end is equipped with a cultivator unit generally referred to by numeral 25. It can be seen that the forward end of the shaft 24 is journaled in the cross member 27.

The drive means for the device comprises the 15 shaft 13 which has a bevel gear 16 driving a gear 17a on a shaft 17 which is connected by a universal joint 18 to a shaft 19b carrying a bevel gear 19a which meshes with a bevel gear 20a on a cultivator carrying shaft 21a. The universal joint 18 allows for flexibility when the 20 frame 6 is adjusted.

A form of cultivator shown in Figure 4 is used for blocking out cotton and this consists of a disk 28 for use on the shaft 24, this disk 28 having 25 arms 29, 29 secured at opposite sides thereof and each provided with hoe-like blades 30 at the outer end thereof.

Figure 5 shows a slightly modified form of 30 blocker, this consisting of a disk 28a, more than two arms 29a which as in the instance of the block shown in Figure 4 have hoe-like blades 30a at their outer ends.

Figure 6 shows a cultivator unit which consists of a disk 31 having a plurality of flexible tines 32 radially disposed therefrom and each provided with an oblique end portion 33.

Figures 1, 2 and 3 show another form of cultivator and this is a disk 34 to the opposite sides of which are secured cross members 35, the ends 40 of which protrude beyond the periphery of the disk 34 and are slightly curved and tapered in opposite directions as at 36, 37 (see Figure 1). This form of cultivator unit serves to jerk or yank out grass and other foreign growths by their 45 roots.

It can be seen that in the form of the invention disclosed, a direct drive between the axle shaft 13 and the cultivating unit is provided.

50 While the foregoing specification sets forth the invention in specific terms, it is to be understood that numerous changes in the shape, size and materials may be resorted to without departing from the spirit and scope of the invention as 55 claimed hereinafter.

Having described the invention, what is claimed as new is:

1. A cultivator comprising a frame, a suspended frame pivotally secured under the first-mentioned frame, means for adjusting the pivotal relation of said suspended frame, cultivator units operative both longitudinally and transversely of crop rows, wheeled means for the first-mentioned frame including a shaft, a transverse shaft on which certain of the cultivator elements are mounted, drive means between the shafts, said drive means including a third shaft having one end geared to one of said first mentioned shafts, a universal connection at the opposite end of said third shaft, and gear means between the universal connection and the other of said mentioned shafts.

2. A cultivator comprising a frame, an axle shaft, wheels secured to the axle shaft, a longitudinally disposed shaft in the frame, a rotary 20 cultivator unit carried by the longitudinal shaft, a transverse shaft in the frame, rotary cultivator units on the transverse shaft, gear means between the transverse shaft and the longitudinal shaft and drive means between the axle shaft 25

and said transverse shaft and said longitudinal shaft, said drive means consisting of a block through which the longitudinal shaft is journaled, said transverse shaft being divided into a pair of sections the inner ends of which are journaled in side portions of the block, gear means between each of the transverse shaft sections and the longitudinal shaft, a shaft connection extending from the longitudinal shaft and gear means between the axle shaft and the shaft extension.

JOHN V. SCHUG.
